UNITED STATES PATENT OFFICE.

WILLIAM H. ANDERSON, OF NEW YORK, N. Y.

CHAIR-BACK DESK.

SPECIFICATION forming part of Letters Patent No. 659,431, dated October 9, 1900.

Application filed July 7, 1900. Serial No. 22,785. (No model.)

To all whom it may concern:

Be it known that I, WILLIAM H. ANDERSON, a citizen of the United States, and a resident of New York, county and State of New York, have invented certain new and useful Improvements in Chair-Back Desks, of which the following is a specification.

This invention relates to a desk adapted to be attached to a chair-back by various adjustments, so as to constitute either a blackboard, a table, or a desk proper.

In the accompanying drawings, Figure 1 is a perspective view of the desk, showing it adjusted to serve as a blackboard; Fig. 2, a central vertical section thereof; Fig. 3, a top view of Fig. 2; Fig. 4, a section on line 4-4, Fig. 2; Fig. 5, a vertical section of the device when adjusted to constitute a table or desk proper, and Fig. 6 a vertical section showing the device adjusted to constitute an extended table.

The letter *a* represents a plate the outer or upper side of which is coated to constitute a blackboard. To the lower side of plate *a* are secured two parallel rails *a'*, and a depending screw *a*² between said rails.

To the plate constructed as above described is adapted to be secured a removable and reversible frame, by means of which the plate may be secured to a chair-back *A* in various positions. This frame consists, essentially, of two parallel rails *b*, adapted to engage the outer sides of the rails *a'*. The rails *b* are connected by three cross-pieces *b'*, *b*², and *b*³. The cross-piece *b'* or fixed jaw has a concave inner face adapted to fit and engage the chair-back. The cross-piece *b*² has a tapped opening through which passes a screw *b*⁴, carrying a convex movable jaw *b*⁵, the whole constituting a vise which co-operates with the fixed jaw *b'* to secure the frame to the chair-back. The cross-piece *b*³ is perforated to admit the screw *a*², carrying a nut *a*³, by means of which the frame is removably and reversibly secured to the plate *a*. To the cross-piece *b*³ are furthermore pivoted a pair of clasps or turn-buttons *b*⁶, by which the device may be suspended from the chair-back. The rails *b* have tongues *b*⁷ formed along their outer sides, which are adapted to be engaged by a pair of grooved rails *c*, carrying bearings *c*'. In these bearings turns a shaft *c*², that passes through the cheeks *c*³ of a shaft *c*⁴. Nuts *c*⁵, mounted upon the outer threaded ends of the shaft *c*² and en-

gaging the bearings *c*', are adapted to clasp the shelf *c*⁴ at any angle desired.

In use the frame is attached to the plate *a* by means of the nut *a*³ in such a manner that the frame will be placed entirely beneath the plate, and then the combined device may be suspended from a chair-back by means of the turn-buttons *b*⁶, Fig. 1. Thus the plate *a* presents an inclined blackboard to the person behind the chair, while the shelf *c*⁴, adjusted at any angle desired, is adapted to hold the chalk and other utensils. If the device is to constitute a table, it is by means of the jaws *b'* *b*⁵ clamped to the chair-back in a slightly-inclined or horizontal position, so that the plate *a* projects over the chair-seat. If the shelf *c*⁴ is secured to the back of plate *a*, (dotted lines, Fig. 5,) the device constitutes a table, while when the shelf is secured to the front of the plate *a* (full lines, Fig. 5) the device constitutes a desk. Finally, the frame may be removed from plate *a*, reversed, and reattached, so as to project rearwardly beyond said plate. If the frame is now clamped to the chair-back by the jaws *b'* *b*⁵, the plate *a* will project a considerable distance farther forward, Fig. 6, to constitute an extended table that projects beyond the chair-seat. Thus it will be seen that by a simple adjustment my improved desk may be transformed into any one of a number of useful articles of furniture.

What I claim is—

1. The combination of a plate with a removable and reversible frame having a pair of jaws and a pair of turn-buttons, and with means for removably securing the frame to the plate, substantially as specified.

2. A plate having a screw and nut combined with a removable and reversible frame having a fixed jaw, a movable jaw, and a perforated cross-piece adapted to be engaged by the screw, and with a shelf having rails adapted to removably engage either end of the frame and to be set to different angles, substantially as specified.

Signed by me at New York city, county and State of New York, this 6th day of July, 1900.

WILLIAM H. ANDERSON.
